ABSTRACT OF THE DISCLOSURE

An input or output circuit for vacuum tubes in high powered, very high and ultra high frequency amplifiers consisting of tunable coaxial line sections coupled such that the coupling remains essentially constant when the circuit is tuned over a prescribed band of frequencies.

This invention relates to electrical apparatus, and more particularly to a coaxial resonator circuit with novel tuning and loading means.

This invention has utility in high powered, very high and ultra high frequency amplifiers, and in other communication applications. In ultra high frequency amplifiers utilizing single ended vacuum tubes of coaxial construction, it is necessary to have continuous tuning over a prescribed band of radio frequencies, and to have adjustable input and output coupling. Prior art coaxial resonator circuits have no provisions for compensating for the change in loading due to such high frequency tuning.

Accordingly, it is a principal object of this invention to provide an improved coaxial resonator output circuit whereby the degree of coupling (loading) remains essentially constant as the resonator is tuned over the band of operating frequencies.

Another principal object of this invention is to provide an improved coaxial resonator input circuit whereby the degree of coupling (matching) remains essentially constant as the resonator is tuned over the prescribed band of frequencies.

Still another principal object of this invention is to provide an improved coaxial resonator circuit wherein the degree of coupling can be varied without any appreciable detuning of the resonant circuit.

Other objects, features and advantages of this invention will suggest themselves to those skilled in the art and will be apparent from the following description of the invention taken in connection with the accompanying drawings in which:

FIG. 1 is a simplified output circuit of the instant resonator;

FIG. 2 is a typical plate-to-ground reactance vs. frequency curve;

FIG. 3 is a resonator current vs. frequency curve;

FIG. 4 is a plot of the reactance of each adjustable coaxial section vs. frequency;

FIG. 5 is a plot of the change of length of each coaxial section between the minimum and maximum operating frequency for various values of the characteristic impedance of each section; and

FIG. 6 is a cross-sectional view of the instant resonator.

Now referring to FIG. 1, the simplified output circuit of the instant resonator shown comprises two adjustable coaxial sections, A₁ and A₂, connected in series with each other and the plate 11 and ground contacts 12 of tube 10. Any conventional type of negative grid electron tube may be used for unit 10. The load resistance, R_L, is shunted across the A₁ coaxial section at points a and a'. The general theory of operation as an amplifier is well known in the prior art and will be assumed without explanation except in so far as the effect of the tuning and loading is concerned.

Now referring to FIGS. 1 and 6, adjustable means, 21 and 22, are provided for changing the effective length of each coaxial section A₁ and A₂; i.e. these adjustable means achieve the desired resonant frequency. As shown,

5 a pair of shorting bars, 23 and 24, slideable along the conductor walls, form end walls in coaxial sections A₁ and A₂ respectively. Axial adjustment of shorting bars, 23 and 24, is achieved by means of plunger rods, 25 and 26, of insulating material projecting out through supports 41 and 42. Short circuiting plungers, 25 and 26, are mechanically linked to common shaft 33. Tuning is accomplished by axial movement of the shaft; the loading adjustment is accomplished by rotation of the shaft.

It is to be noted in FIGURE 6 that use of suitable bypass condensers, 18 and 19, and insulator 17 isolates the D.C. anode voltage from the wall conductors.

The instant invention provides a resonator that is continuously tunable over a prescribed band of frequencies by maintaining the following derived theoretical relationship between the reactances of each coaxial section over the frequency range.

For resonance:

$$X_1 + X_2 = -X_{pg} \quad (1)$$

Where:

$$R_L \gg X_1$$

X₁ is the reactance of section A₁

X₂ is the reactance of section A₂

X_{pg} is the plate-to-ground reactance of the vacuum tube

Since

$$X_1 = Z_1 \tan \beta L_1$$

$$X_2 = Z_2 \tan \beta L_2$$

Where:

L₁ is the length in meters of section A₁

L₂ is the length in meters of section A₂

β is the propagation constant in radians/meter

Then:

$$X_1 + X_2 = Z_1 \tan \beta L_1 + Z_2 \tan \beta L_2 = -X_{pg} \quad (2)$$

Therefore any finite value of Z₁ and Z₂ can be used except Z₁=Z₂=0, where Z₁ is the characteristic impedance in ohms of coaxial section A₁, and Z₂ is the characteristic impedance of coaxial section A₂.

It is to be noted that the plate-to-ground reactance, X_{pg}, of vacuum tube 10 is a function of frequency. I_a is a function of frequency and plate voltage swing. The plate voltage swing will normally remain constant for a given class of tube operation for different frequencies. A typical plate-to-ground reactance vs. frequency curve is shown in FIG. 2.

As the resonator is tuned over the prescribed band of frequencies, the degree of coupling (loading) is made constant by selecting values of Z₁ and Z₂ such that ΔL₁=ΔL₂ in accordance with the following theoretical relationship.

For proper loading:

$$P_o = \frac{(E_{aa'})^2}{R_L} = \frac{(I_a X_1)^2}{R_L} \quad (3)$$

Where:

P_o is the required power output

E_{aa'} is the voltage drop across section X₁

I_a is the resonator current in the aa' plane.

65 From Equations 1 and 3, X₁ and X₂ can be determined in terms of P_o, I_a and X_{pg}.

$$X_1 = \sqrt{\frac{P_o R_2}{I_a}} \quad (4)$$

$$X_2 = -(X_{pg} + X_1) \quad (5)$$

Therefore, to achieve constant loading, it is necessary to determine values of Z_1 and Z_2 (characteristic impedance) so that: short circuiting plungers 25 and 26 of coaxial sections A_1 and A_2 can be mechanically linked together; the circuit can be tunable from $f_{\min}$ to $f_{\max}$; and simultaneously, without changing the mechanical link, the voltage drop $E_{aa'}$ remain constant.

The following procedure is used:

(1) The values of X_1 vs. frequency are plotted as shown in FIG. 4. The values are obtained in accordance with Equation 4, and from a plot of resonator current, I_a , vs. frequency shown in FIG. 3.

(2) From Equation 5, a curve of X_2 vs. frequency is plotted as shown in FIG. 4.

(3) From an actual measurement of the amount of movement of plunger 25, or change of length of L_1 between $f_{\min}$ and $f_{\max}$ for various values of Z_1 , a plot of ΔL_1 vs. Z_1 is made as shown in FIG. 5.

(4) Using FIG. 4 for values of X_2 , a plot is made of the change of length of L_2 between $f_{\min}$ and $f_{\max}$ for various values of Z_2 , as shown in FIG. 5.

By selecting values of Z_1 and Z_2 from FIG. 5 such that $\Delta L_1 = \Delta L_2$, essentially constant loading over the prescribed tuning range from $f_{\min}$ to $f_{\max}$ can be obtained. For example, in FIG. 5 it is seen that for $Z_1 = 4$ ohms and $Z_2 = 28$ ohms, $\Delta L_1 = \Delta L_2 = 7.4$ cm. These values are practical. However, it is to be noted that in selecting Z_1 and Z_2 , other factors such as voltage gradient and stored energy must be considered.

Means of varying the degree of coupling without an appreciable detuning of the resonant circuit is accomplished in the following manner:

It is necessary to change the reactance of section A_1 , X_1 , for a given frequency; thus, an increase in X_1 will result in an increased voltage across the load R_L . But when reactance X_1 is increased, reactance X_2 must be decreased by the same magnitude to maintain resonance; that is, to avoid detuning, $\Delta X_1 = -\Delta X_2$ (frequency constant). This relationship between the reactances of the two sections is accomplished by maintaining the following relationship between L_1 and L_2 :

Since

$$X_1 = Z_1 \tan \beta L_1$$

$$X_2 = Z_2 \tan \beta L_2$$

$$\frac{dX_1}{d\beta L_1} = Z_1 \sec^2 \beta L_1 \text{ ohms/radian}$$

$$\frac{dX_2}{d\beta L_2} = Z_2 \sec^2 \beta L_2 \text{ ohms/radian}$$

For:

$$dX_1 = -dX_2$$

$$Z_1 \sec^2 \beta L_1 d\beta L_1 = -Z_2 \sec^2 \beta L_2 d\beta L_2$$

Or:

$$Z_1 \sec^2 \beta L_1 dL_1 = -Z_2 \sec^2 \beta L_2 dL_2$$

$$\frac{dL_2}{dL_1} = -\frac{Z_1 \sec^2 \beta L_1}{Z_2 \sec^2 \beta L_2}$$

$$\frac{\Delta L_2}{\Delta L_1} = -\frac{Z_1 \sec^2 \beta L_1}{Z_2 \sec^2 \beta L_2} \quad (7)$$

Thus, Equation 6 is the relationship between L_1 and L_2 , the length in meters of sections Z_1 and Z_2 respectively, required in order to maintain resonance while changing loading. Since the relationship in Equation 6 cannot be maintained exactly over a band of frequencies, a practical solution is to solve Equation 6 for the center frequency, F_c .

It should be noted that plungers 25 and 26 can be operated independently to obtain proper loading when used as an output circuit, or to obtain proper matching when used as an input circuit. In such a case, there would be no specific relationship between the impedances of the Z_1 and Z_2 sections, and Equation 6 would not necessarily hold.

While there has been described what is at present considered to be the preferred embodiment of this invention, it will be obvious to those skilled in the art that various changes and modifications may be made therein without departing from the scope of the invention as set forth in the appended claims.

What I claim is:

1. A coaxial resonator circuit comprising an electron tube having an anode, a ground contact and an anode-to-ground reactance, a load, a first and second coaxial section each having a reactance, said coaxial sections serially connected to each other and to said anode and to said ground contact and to said load, adjustable means for each of said coaxial sections to cause the sum of the reactances of said first and second sections to equal said tube anode-to-ground reactance.

2. A coaxial resonator circuit for varying the degree of coupling to a load without appreciably detuning said circuit comprising: a vacuum tube of coaxial construction, a load, a first and second coaxial section connected in series with each other, short circuiting plunger means insertable in each of said coaxial sections, common means for driving said plungers, said first coaxial section connected to the anode of said tube and to said load, said second coaxial section connected to a ground contact point of said tube and to said load, said first and second coaxial sections coating to provide essentially constant loading over the operating frequency tuning range by causing the change in length of said first section to be equal to the change in length of said second coaxial section.
